MEANS FOR THE MANUFACTURE OF PADS
OR SHEETS COMPOSED OF FIBERS OF
KAPOK OR THE LIKE MATERIALS

Charles Norman Mims, Paris, France

Application June 19, 1934, Serial No. 731,338
In France February 7, 1934

4 Claims. (Cl. 112—2)

It is known that the working-up of pure kapok into sheets, owing to the nature of kapok fibers, can not be effected in the same manner as the working-up of wool or cotton into sheets. A 5 special contrivance is necessary for the purpose, so as to allow the kapok fiber to retain its length and to avoid breaking it and thus causing it to lose its valuable properties.

The subject-matter of the present invention 10 is a means for the manufacture of pads or sheets composed of kapok or the like fibers, which enables these products to be made available as wadding, in which form they may be applied to a large number of uses.

15 The sheet made in this way retains its uniform nature. The fibers are not broken, which is the most important feature, and the sheet so made weighs about one-sixth of a similar sheet made of cotton or wool. It is impervious, unattacked 20 by parasites, an insulator of heat and cold, and is moreover very buoyant in water.

According to the invention the kapok is freely laid in a more or less thick layer between two plates provided with slits, which enable lines of 25 stitches to be sewn very quickly by a sewing means, so as to join the fibers together without breaking them.

It is an essential feature of the invention, that 30 no other pressure is exerted upon the layer of the assembled kapok except that of the needle holder or specially made presser-foot at the moment of the needle sewing stitches across the sheet.

The stitching can be done directly on the bare 35 sheets or on fabrics which hold them.

It can moreover be effected through one or two sheets of paper, which are afterwards torn off along the stitched lines when they have assisted in holding the kapok together and facilitated its working-up into pads or sheets.

40 The invention will be better understood by means of the following description and with reference to the accompanying drawing which shows:

Figure 1 is a top plan view of the pressing plate,

Figure 2 is a vertical sectional view of the present invention in use,

Figure 3 is a top plan view of Figure 2 and

50 Figure 4 is a top plan view of the adjustable pressing plate.

The device according to the invention comprises a frame formed by two plates 1 and 2, held one over the other by means of pins 3 fastened on the lower plate 1.

55 The plates 1 and 2 are provided with longi-

tudinal openings 4, which lie over each other in the two plates.

The plate 2 moves freely in a vertical direction on the pins 3, which may be formed by round, square or rectangular bars, or even by 5 small plates which pass through openings 3' in the plate 2.

The pins are arranged on one side only of the frame, which permits three sides of the frame to be left free.

10 The apparatus is very simple to use.

The kapok is spread in small tufts on the plate 1, care being taken not to break the fibers. Then when a certain height has been reached, the plate 2 is put into position over the kapok, 15 the pins 3 being inserted in the holes of the plate 2.

The whole frame can then be moved and placed upon a sewing machine, which may be of the ordinary household type, workroom type or 20 of the special type used by harness-makers, or special type, depending on the thickness of the sheet.

On the machine there is arranged a pressure foot 7 fitted with a base having two rollers, or 25 shoes or a foot 8 with rollers 9. The rollers 9 travelling over the several solid parts 5 of the plate 2 and which are situated on both sides of the openings 4 wherein the needle 10 works as shown in Figs. 2 and 3. The base part used thus 30 presses on the plate 2 and compresses the kapok 11 so as to keep it from moving during the sewing operation.

The length of the needle to be used obviously 35 depends on the thickness of sheet formed.

The kapok may be placed directly into the frame and sewn bare, or a cloth may be put over the top part, or again two cloths may be used, one on each side of the pad.

Two sheets of paper, one on each side of the 40 pad, may likewise be used in order to facilitate the assembly of the kapok between the plates 1 and 2. The pad and the papers may be stitched together, and the papers may afterwards be easily torn away along the stitched lines, so as to leave 45 the pad or sheet bare on its two surfaces.

It is obvious that a cloth and a sheet of paper could also be used in combination, as well as any other material (skin, flexible substance, etc.).

The dimensions of the plates are slightly 50 larger than those which the finished sheets are to have. Thus, in order to obtain sheets having a width of 50 cm. the frame will have to be about 60 cm., owing to the edges of the plates and the pins. The sheets may however have a greater 55

width than the frame, since this is open on three sides to give a clear passage to the pad. The stitched pad can in fact be slipped to one side and, after the plate 2 has been removed, a fresh quantity of kapok can be assembled which, after the plate 2 has been replaced, will be stitched after the pad already made and joined to it.

The sewing obtained with the frame shown in Figure 1 is perpendicular to the small sides of the rectangular pad.

If it is desired to obtain oblique pads, in the shape of parallelograms, a frame may be used which is adjustable in shape (Figure 4). In this case the plates are formed by the bars 6, 15 which are hinged at their ends to the bars 7 forming the small sides.

The sheets so made may be put to the most varied uses.

They may be used for lining clothing, tapes-
tries and hangings, etc.

They can easily be used in the manufacture of lifesaving clothing or apparatus.

They can also be used in articles of travel and for lining trunks, to prevent the contents from being spoiled by damp.

They will make excellent stuffing material for the upholstery of all kinds of motor-cars.

They can be usefully employed for heat-insulating purposes in footwear, in buildings and in connection with heating installations or ice-chests and refrigerators etc.

The sheets can also be used with advantage to replace the wadding used for medical purposes.

It is evident that modifications of shape or of details may be made in the apparatus described above by way of example only, without departing from the spirit of the invention.

What I claim is:

1. In a device of the character described

adapted to be used in connection with a sewing machine comprising a pair of opposed plates, said plates having longitudinal and aligning openings therein through which may pass the needle of the sewing machine, means for loosely connecting said plates, a presser foot comprising a plurality of compression rollers carried by said sewing machine and one of said plates having a flat outer surface whereby the presser foot of the sewing machine may travel thereupon.

2. A device of the character described comprising a pair of spaced plates, each plate consisting of a plurality of spaced bars having means for hingedly connecting said bars whereby the spaces between said bars may extend at various angles from said means substantially as and for the purpose specified.

3. The combination with a sewing machine of means for retaining pads or sheets composed of fibers of kapok or the like material comprising a pair of plates having parallel longitudinal openings formed therein, means for loosely connecting said plates together, the needle of said sewing machine passing through said parallel openings and a plurality of compression rollers carried by the sewing machine for applying pressure upon one of said plates in close proximity to the needle of the sewing machine.

4. The combination with a sewing machine for the formation of pads or sheets composed of fibers of kapok, of means for retaining a felted layer of said kapok while the fibers thereof are being sewed together, said means comprising an upper plate and a lower plate for receiving the kapok fibers therebetween, and means mounted on said lower plate for guiding said upper plate in a vertical direction for conserving the elasticity of the fibers of kapok.

CHARLES NORMAN MIMS.
